DESIGN FOR A TEXTILE FABRIC

Albert F. Schlatter, New York, N. Y.

Application June 5, 1940, Serial No. 92,829

Term of patent 3½ years

To all whom it may concern:

Be it known that I, Albert F. Schlatter, a citizen of the United States of America, residing in New York city, in the Borough of Manhattan, county and State of New York, have invented a new, original, and ornamental Design for a Textile Fabric, of which the following is a specification, reference being had to the accompanying drawing, forming part thereof, wherein,

The figure is a plan view of a piece of textile fabric showing my new design.

I claim:

The ornamental design for a textile fabric, substantially as shown.

ALBERT F. SCHLATTER.
